REPEAT TYPING MECHANISM FOR POWER-
OPERATED TYPEWRITERS AND LIKE MA-
CHINESWilliam H. Kupper, West Hartford, Conn., as-
signor to Royal Typewriter Company, Inc., New
York, N. Y., a corporation of New York

Application September 29, 1950, Serial No. 187,587

9 Claims. (Cl. 197—17)

1

This invention relates to power operated typewriters or like machines, and more particularly to repeat typing mechanisms for such machines.

Some power operated typewriters or like machines now known include mechanism responsive to manipulation of a repeat key for automatically effecting repeated typing strokes of a typing member. In one class of such mechanisms an actuator connected to the typing member is adapted to be connected transiently to a continuously driven member, such as a snatch roll, by depression of a repeat key which is equipped or associated with means for automatically effecting re-connection of the actuator with the driven member at or near the end of each operating cycle of the typing member, as long as the repeat key is held depressed.

An object of the present invention is to provide a power operated typewriter or like machine having repeat typing mechanism of the general class referred to which is of improved construction, is certain and reliable in operation, and which is capable of withstanding long and frequent use.

Other objects of the invention will become apparent from a reading of the following description, the appended claims, and the accompanying drawings, in which:

Figure 1 is a view, partly in elevation and partly in vertical section, fore and aft of a typewriter embodying the invention, showing only some of the conventional or standard typewriter parts in order to illustrate the application of mechanism embodying the invention to a typewriter construction, the parts being shown in their normal or inactive positions;

Figure 2 is a detail horizontal section on the line 2—2 of Figure 1;

Figure 3 is a fragmentary view, partly in vertical section fore and aft of the machine, showing a type bar actuator and associated parts in the positions they occupy when the type bar is substantially in printing position, and showing a repeat typing mechanism in operated position in readiness for effecting another type bar operation upon returning of the type bar towards its normal position;

Figure 4 is a view similar to Figure 3 but showing the parts in the positions they occupy when the repeat mechanism, positioned as shown in Figure 3, is effective for causing another or repeat typing operation; and

Figure 5 is a detail view in side elevation showing a type bar head.

The invention may be embodied in typewriters or like machines of various kinds. For the purposes of illustration, the invention is shown as being embodied in an office type typewriter having, except for the power generating and transmitting mechanism to be described, many features in common with the well known Royal

Standard typewriter. The drawings show only enough of the standard or known typewriter construction to assist in illustrating the manner in which mechanism embodying the invention may be coordinated with other parts of a typewriter construction. The known construction illustrated includes a main frame A on which a carriage equipped with a platen is mounted for letter spacing and return movements by means of a top rail 1 secured to and forming part of the carriage, and rolling upon balls 2, which in turn are adapted to roll on a frame-mounted bottom rail or track 3.

The carriage may be driven toward the left, that is, in the letter-spacing direction, by any suitable mechanism, for example, by a spring barrel and draw band (not shown) of known or suitable construction. Carriage returning mechanism may be of the kind disclosed in the co-pending application of Henry J. Hart, Serial No. 21,476, filed April 16, 1948, now United States Patent No. 2,567,937, issued September 18, 1951, or of other suitable construction, preferably power-operated.

A case shift segment element 4 is mounted to shift vertically on the frame A by a construction not shown but which may be of a well known form. Mechanism for shifting the segment includes a link 5 pivoted as at 6 to the segment and pivoted as at 7 to an arm 8 mounted on a shaft 9 extending lengthwise of the typewriter and mounted in any suitable manner at its opposite ends on the frame A. As in the standard Royal office typewriter, the shaft 9 may be equipped at both ends with a rock arm 8, and both of the arms 8 may be associated with links 5. Counterbalancing springs, one of which is shown at 10, are interposed respectively between fixed studs 11 on the frame A and pins 12 projecting forwardly from the segment 4.

The counterbalancing springs 10 normally maintain the type bar segment 4 in its upper position with respect to the frame, which is in its lower case position for the purposes of typing. In order to shift the segment 4 downwardly to its upper case position, the shaft 9 is rocked counterclockwise by mechanism to be described.

In order to retain the segment 4 in its raised, or lower case position so as to prevent accidental displacement which might be caused by vibration incident to operation of the machine, a segment lock or anti-vibration device, generally designated 13, is provided. The device 13 comprises a cushion spring 14 carried by a mounting member 15 secured to the segment 4 by a screw 16, and a shift lock or dog 17 pivoted on the frame at 18 and normally engaging the bottom of the spring 14.

The segment 4 is provided with the usual arcuate pivot wire 19 on which the usual complement of typing members, one only of which is

shown at 20 as a front strike type bar, is pivoted. The type bar 20, as shown in Figure 5, has a lower case typing character 20^a and an upper case typing character 20^b which, in the form shown, is an underscoring or underlining character.

In general, the construction described so far is of a known kind and does not in itself constitute the present invention. The invention resides in other parts to be described, and the 10 combinations of such other parts with each other and with the parts described above.

Broadly considered, operation of the type bar 20 is effected by power-driven means, generally designated D, adapted to be made effective by 15 depression of a single-stroke typing control key E, or a repeat stroke typing control key F. The power-driven mechanism D is generally similar to but embodies improvements in mechanism disclosed in the co-pending application of William H. Kupper, Serial No. 6,066, filed February 3, 1948, now United States Patent No. 2,567,945, issued September 18, 1951. It includes a driving element, which operates continuously, and controllable driving connections, which normally are 20 inoperative or ineffective, but which may be conditioned by the operator to effect operative driving connection between the continuously moving driving member and the type bar 20. The driver preferably is constituted by a rotatable continuously driven member, more particularly a toothed snatch roll or bar 21, which may be of known form, and which is adapted to be driven in the direction of the arrow a in the Figure 1 by any suitable means, but preferably by an 35 electric motor (not shown).

The means for transmitting drive from the driver 21 to type bar 20 includes an actuator 22 which extends fore and aft of the typewriter and above the member 21. The actuator 22 is pivoted as at 23 to a lever 24 at a point off-set relatively to the pivotal mounting 25 of the lever on a fixed frame cross bar 26. The actuator 22 is connected to the type bar 20 by a link 22^a and has a forwardly extending part 27 projecting under an abutment or guide plate 28 mounted on the frame A to extend parallel to the snatch roll 21. A spring 29, interposed between the front end of the actuator 22 and an anchor plate 30, yieldably urges the actuator to rock clockwise, and thus normally maintains the actuator in the position shown in Figure 1 with its front end part 27 bearing against the abutment or guide plate 28. Another abutment 31 is disposed below the abutment 28, and is slotted to receive and guide the lower extremity of the actuator part 27 for sliding movements. The lever 24 normally is held in its inactive position, shown in Figure 1, by a returning spring 32 interposed between a part (not shown) at the rear of the frame A and a wire link 33 pivoted at 34' to the lever 24.

In order to apply a power impulse to the type bar 20, the actuator 22 is operatively but indirectly connected to the driving member 21, the actuator itself never engaging the driving member. Mechanism for bringing about this operative connection includes an interponent pawl element 34, pivoted as at 35 on the actuator. A spring 36, anchored to the actuator 22 and connected to the pawl 34, biases or urges the latter to rock clockwise so as to move its nose into engagement with the snatch roll 21. Normally, the pawl is maintained out of engagement with the snatch roll by the restraining action of a con-

trol element or trigger 37 which is pivoted as at 38 on the actuator 22. In the normal position of the trigger, its rear end or nose engages a holding surface 39 on the pawl so as to prevent the spring 36 from rocking the pawl 34 into drive-transmitting engagement with the driving member 21. The pawl 34 is formed with an inclined resetter cam face 40 which is located just below the holding surface 39, and which is acted upon by the trigger nose for rocking the pawl counterclockwise, and thus resetting it in normal, inoperative position.

The mechanism for effecting single operations of the type bar 20 includes the key lever E pivoted on a fixed part 41 of the frame as at 42. An upward extension 43 on the rear end of the key lever E projects behind the depending arm 44 of a lever 45 pivoted at 46 on a frame cross bar 47. Pivoted at 48 on another arm 49 of the lever 45 is a limber dog or flipper 50 urged clockwise by a spring 51 but limited in its clockwise movement by a stop ear 52 on the lever arm 49. The lower end of the flipper 50 is disposed above a contact ear 53 on the type bar actuator 22. A tension spring 54 interposed between the key lever E and an arm 55 on the lever 45, and a compression spring 54^a interposed between the lever arm 55 and an anchor plate 54^b on the cross bar 47 normally maintain the parts in the positions shown in Figure 1.

In operation, when the single impression character key lever E is depressed the lever 45 is rocked clockwise, causing the flipper 50 to engage the actuator ear 53 and move the actuator 22 downwardly until its associated trigger 37 is rocked to pawl-releasing position by engagement with the lower abutment 31. The pawl or interponent 34, having been thus released, will move into engagement with the snatch roll 21 so as to be driven forwardly together with the actuator 22, thus rocking the lever 24 and actuating the type bar 20 through the link connection 22^a.

When the pawl 34 is cast off from engagement with the snatch roll 21, the spring 29 lifts the actuator 22 to bring the trigger 37 into engagement with the upper, trigger-resetting abutment 28. This causes the trigger 37 to be rocked counterclockwise, so as to move its rear end against the resetting cam face 40 of the pawl 34, thereby restoring the latter to its inactive position. The type bar 20 and its operating connections will then be restored to their normal positions, shown in Figure 1, by the spring 32, previously referred to.

Means are provided for adjusting or varying the amount of driving impulse generated by the power mechanism D. This variation or adjustment is effected by variably limiting the extent to which the tooth on the actuator pawl nose enters tooth interspaces on the snatch roll 21 under the urge of the spring 36 when the restraint of the trigger 37 on the pawl 34 is discontinued. In the form shown, the actuator 22 is provided with a downwardly extending stop element or finger 56 which is disposed in front of and normally out of contact with a downwardly extending stop part, heel, or finger 57 on the pawl 34. When the pawl 34 is rocked clockwise by the spring 36 so as to move the pawl tooth into a snatch roll tooth interspace, the pawl stop 57 moves toward the actuator stop 56, which may be so positioned as to be engaged by the stop 57 to arrest the rocking of the pawl 34 before the pawl tooth moves to the root of the snatch roll 75 tooth interspace. By variably positioning one

of the stops 56, 57, e. g., by bending the stop 56 towards or away from the stop 57, the extent to which the pawl tooth enters the tooth interspace on the snatch roll can be varied. Consequently, the angle through which the snatch roll 21 rotates while in contact with the pawl 34, which determines the amount of driving of the pawl 34 and actuator 22 by the snatch roll 21, can be varied. Any suitable means or construction may be provided for adjusting one of the stops 56, 57 relatively to the other, but in the preferred construction the stop 56 is formed integrally with the actuator 22 so as to be bendable toward or away from the stop 57.

In typewriters or like machines in which all or some of the instrumentalities to be operated, e. g., type bars, carriage return mechanism, tabulating mechanism, escapement mechanism, back spacing mechanism, and case shift mechanism, are operated by power, it may be desirable to provide means for varying collectively the extent of driving of the several actuator pawls corresponding to the pawl 34 and associated with the other mechanism referred to. This may be accomplished by providing a knock-off bar 58 mounted on the main frame so as to extend under the front ends of all of the actuators corresponding to the actuator 22 shown in Figure 1. Any suitable means (not shown), may be provided for adjustably tilting or otherwise variably positioning the knock-off bar 58 so that it will be engaged by the lower ends of the actuators to control the timing of disengagement of the associated actuator pawls from the snatch roll.

Mechanism is provided for effecting automatically repeated operation of the power operated mechanism D for causing the type bar 20 to perform a succession of typing strokes when the repeat key lever F, previously referred to, is depressed and held down. The key lever F is pivoted at 59 on a fixed frame part 60 and is urged clockwise as viewed in Figure 1 by a spring 61 interposed between the rear end portion of the lever F and a stud 62 on the frame part 60. Rocking of the lever F to its normal position under the urge of the spring 61 is limited by engagement of a stop part 63 on the lever with the rear edge 64 of the frame part 60. Counterclockwise rocking of the key lever F against the urge of the spring 61 for effecting repeated typing operations is limited by engagement of another stop part 65 on the lever with the rear edge of the frame part 60.

A wire link 66 is pivoted at its upper end to the rear end of the key lever F, and is pivoted at its lower end to the rear end of a lever 67 pivoted at 42 on the frame cross bar 41. A flat link 68 is pivoted at 69 to the lever 67 between the pivot 42 and the connection of the lever 67 to the link 66, and is pivoted at 70 to a curved arm 71 secured, as by brazing or welding, to a rock shaft 72 journaled at 73 and 74 on the main frame. The arm 71 is curved as shown in Figure 1 so as to enable it to be bent or maulled easily for varying its effective lever arm length and hence the relative movements or timing of the operation of the parts which it connects.

Also secured as by brazing or welding to the shaft 72 is an arm 75 (see especially Figures 3 and 4) which has a part 76 overlying an ear 77 on a settable contactor element 78 pivoted at 79 on a bracket 80 secured adjustably to the bar 58 by screws 81. The element 78 has a contactor surface 82 which normally is disposed to the rear of and in spaced relationship to a pin 83 on the bottom end of a tail 84 on the trigger 37. Nor-

mally, the parts are in the position shown in Figure 1 so that the contactor face 82 cannot engage the pin 83 on the trigger tail 84. Consequently, the positioning of the trigger 37 will be controlled by the movements of the actuator 22 and the engagement of the trigger with the abutments 31 and 28, as previously described, so that single stroke typing operations may be performed under the control of the key E and its associated mechanism.

When it is desired to cause the type bar 20 to perform automatically a succession of typing operations the repeat key F is depressed and held down. Depression of the key F will raise the link 66 to rock the lever 67 counterclockwise, lift the flat link 68, and rock the arm 71, the shaft 72 and the arm 75 clockwise. The part 76 of the arm 75 will press downwardly on the ear 77 of the contactor 78, and rock the latter counterclockwise against the urge of a normalizing spring 85 interposed between the ear 77 and the shaft 72. The contactor 78 will then move to and be set in the position shown in Figures 3 and 4, so as to engage the pin 83 on the trigger tail 84 and rock the trigger 37 clockwise, thereby moving the rear end of the trigger below the holding surface 39 on the pawl 34, and enabling the spring 36 to rock the pawl into engagement with the snatch roll 21. In this manner, the pawl 34 and actuator 22 will be operatively connected to the snatch roll 21 without first lowering the actuator 22, as is necessary for effecting connection of the pawl and actuator to the snatch roll when the single stroke key E is depressed.

After the pawl 34 has been moved into engagement with the snatch roll 21, the pawl and actuator will be moved forwardly as a unit to drive the type bar 20 to printing position. When the pawl 34 has been cast free of engagement with the snatch roll the spring 29 will move the actuator 22 upwardly to bring the trigger into engagement with the resetting abutment 28, and the spring 32 will rock the lever 24 clockwise to move the actuator 22 rearwardly towards its normal position. When the actuator approaches its normal position the pin 83 on the trigger tail 84 will re-engage the surface 82 on the contactor 78 so as to prevent the trigger 37 from remaining in or being returned to its normal position in which it holds the pawl 34 disengaged from the snatch roll 21. Consequently, just before the actuator reaches its normal position, the pawl 34 will be so positioned as to re-engage the snatch roll 21, causing the pawl and the actuator 22 again to be driven forwardly with a consequent further typing stroke of the type bar 20. This sequence of operations will be repeated cyclically until the repeat key F is released to permit the spring 61 to return the key and the contactor 78 to their normal positions, so that the contactor face 82 cannot again engage the pin 83 on the trigger tail 84. When the pawl 34 is cast free of the snatch roll 21, the spring 29 will raise the actuator 22 during its return stroke so as to bring the trigger 37 into engagement with the resetting abutment 28, thereby rocking the trigger 37 counterclockwise about its pivot 38, unrestrained by the contactor 78, and causing the rear end of the trigger to act on the resetting cam face 40. This will return the pawl 34 to its normal position, enabling the parts to come to rest.

Any suitable means may be employed for rocking the shaft 9 to effect case shifting movements of the type bar segment 4. Preferably, a power operated means such as that disclosed in the co-

pending application of William H. Kupper, Serial No. 133,322, filed December 16, 1949, now United States Patent No. 2,590,777, issued March 25, 1952, is provided. Only parts of this power operated mechanism are disclosed herein, reference being made to the aforesaid co-pending application for a more detailed description. Included in the case shifting mechanism shown is an adjustable link 86 adapted to be driven by an actuator similar to the actuator 22 so as to transmit case shifting effort to the shaft 9 through a cushioned drive-transmitting device generally designated 87.

The cushion lever device 87 includes a lever arm 88 which is fast on the shaft 9 and which is formed with a rearwardly extending part 89 provided with a plurality of spring seats 90. Another lever arm 91, pivoted as at 92 on the arm 88, is provided with a pin projection 93 which is movable in a slot 94 in the lever arm 88, the ends of the slot 94 being engageable by the pin 93 for limiting relative rocking or pivotal movement of the lever arms 88 and 91. A drive-transmitting spring 95 is interposed between the arm 91 and one of the spring seats 90 which may be selected for varying the effect of the spring in urging the lever arms 91 and 88 to rock toward each other.

The rear end of the link 86 is pivoted to the arm 91 by a pin 96 secured to the lever arm 91 and projecting into a horizontally extending slot 97 in the rear end of the pull link 86. Normally, when the parts are in the positions shown in Figure 1 with the segment 4 in its raised, or lower case position, the pin 96 is at the front end of the slot 97.

In operation, when the link 86 is pulled forwardly by power transmitted from the snatch roll 21, e. g. through the medium of mechanism of the kind disclosed in application Serial No. 133,322, now United States Patent No. 2,590,777, issued March 25, 1952, referred to above, the lost motion at the pivot 96-97 will be taken up. Thereafter, the rear end of the slot 97 will engage the pin 96; and the lever arm 91 will be rocked counterclockwise. This will exert a pull on the cushioning, force-transmitting spring 95, resulting in rocking the lever arm 88 counterclockwise, with consequent counterclockwise rocking of the shaft 9 and the rock arms 8 so as to pull the links 5 and segment 4 downwardly. During the initial forward movement of the link 86, and prior to rocking of the lever arm 91, the segment locking dog 17 is withdrawn from engagement with the spring abutment 14 by a link 98 interposed between the locking dog 17 and an ear 99 on the link 86.

The case shifting mechanism is controlled by a shift key structure including a left shift key lever 100 and a right shift key lever 101 united by a bar 102 so as to be depressible or rockable as a unit about a pivot 103 on the frame cross bar 41. The left shift key lever 100 is formed with an upper extension 104 projecting behind a lever corresponding to the lever 45 previously referred to. The arrangement is such that, when the shift key structure 100-101-102 is depressed or rocked about its pivot 103, the extension 104 operates its associated lever so as to effect connection of the snatch roll 21 with an actuator similar to the actuator 22 and to which the link 86 is connected, whereby the link 86 will be pulled forwardly and held in its actuated position by mechanism described in detail in application Serial No. 133,322, now United States Patent No.

2,590,777, issued March 25, 1952, previously referred to.

A shift lock key 105 is pivoted as at 103, and is equipped with a pin 106 overlying a tail 107 on a detent or pawl 108 which is pivoted at 109 on the left shift key 100. The pawl 108 is formed with a notch 110 which normally is disengaged from an ear 111 fixed to the frame A, the pawl 108 being held in the normal position shown in Figure 1 by a spring 112 connected to the pawl and anchored at 113 on the left shift key lever 100. In operation, when the shift lock key 105 is depressed, its pin 106 presses on the tail 107 of the pawl 108 so as to rock the rear and upper end of the pawl into engagement with the flat rear face of the fixed ear 111, which stops rocking of the pawl relatively to the shift lock lever 105. Further depression of the shift lock lever 105 then causes downward movement of the left shift key 100 on which the pawl 108 is mounted, thus causing the segment shifting mechanism to operate as previously described. During a slight further downward movement of the shift lock lever 105, the front edge of the rear end of the pawl 108 will move below the ear 111, permitting the pawl to rock a little further so as to enable the notch 110 in the pawl to receive the lower edge of the fixed ear 111. When, thereafter, pressure on the shift lock key is removed, the pawl 108, now being operatively engaged with the ear 111, will hold the shift lock key 105 and the shift key structure 100-101-102 depressed. In order to return the parts to their normal positions, the shift key structure 100-101-102 is depressed so as to permit the spring 112 to return the pawl 108 to its normal, non-latching position. Then, upon relieving pressure on the shift key structure 100-101-102, the parts will be returned to their normal positions by a normalizing spring 114 connected between the right shift key lever 101 and the anchor plate 30.

The construction described with reference to the accompanying drawings embodies the invention in a preferred form, but it is intended that it be considered as illustrative rather than definitive of the invention. The invention is defined in the claims.

I claim:

1. In a power operating mechanism for a typewriting or like machine, a typing member; a power-driven member; an actuator; means connecting said actuator to said typing member; an interponent rockably mounted on said actuator for movement into operative engagement with said driven member and for reverse movement out of operative engagement with said driven member, and being biased to rock in one direction from a normal position in which it is disengaged from said actuator into operative engagement therewith; a trigger movably mounted on said actuator and normally maintaining said interponent disengaged from said driven member; a typing control mechanism including a settable element engageable with said trigger for moving said trigger to release said interponent and enable it to rock in said one direction into engagement with said driven member whereby said actuator will be driven by said driven member to operate said typing member during the course of which operation said interponent is thrown out of engagement with said driven member; means for then returning said actuator towards its normal non-actuated position; and means for rocking said interponent in the reverse direction to

return it to its normal position, said typing control mechanism including a manipulatable member operable for moving said settable element to its set position for engaging said trigger when said manipulatable member is operated, and for maintaining said settable member in its set position for repeatedly re-engaging said trigger when said manipulatable member is held in manipulated position thereby to prevent returning of said trigger to its normal position, whereby, during returning of said actuator towards its normal non-actuated position, said interponent will re-engage said driven member to be repeatedly driven thereby for effecting repeated driving of said actuator and repeated typing operations of said typing member.

2. In power operating mechanism for a typewriting or like machine, a typing member; a power-driven member; an actuator; means connecting said actuator to said typing member; an interponent mounted on said actuator for movements into and out of operative engagement with said driven member and being biased to move from a normal position in which it is disengaged from said actuator into operative engagement therewith; a trigger normally maintaining said interponent disengaged from said driven member; a typing control mechanism including a settable element engageable with said trigger for moving said trigger to release said interponent and enable it to move into engagement with said driven member whereby said actuator will be driven by said driven member to operate said typing member during the course of which operation said interponent is thrown out of engagement with said driven member; means for then returning said actuator towards its normal non-actuated position; means for returning said interponent to its normal position in response to returning of said trigger to its normal position, said typing control mechanism including a manipulatable member operable for moving said settable element to its set position for engaging said trigger when said manipulatable member is operated, and for maintaining said settable member in its set position for repeatedly re-engaging said trigger when said manipulatable member is held in manipulated position thereby to prevent returning of said trigger to its normal position, whereby, during returning of said actuator towards its normal non-actuated position, said interponent will re-engage said driven member to be repeatedly driven thereby for effecting repeated driving of said actuator and repeated typing operations of said typing member; and trigger re-setting means operable when said settable element has been returned to its normal position in which it is not engageable with said trigger, for returning said trigger to its normal position and thereby returning said interponent to its normal position on said actuator.

3. In power operating mechanism for a typewriting or like machine, a typing member; a power-driven member; an actuator; mean connecting said actuator to said typing member; an interponent mounted on said actuator for movements into and out of operative engagement with said driven member and being biased to move from a normal position in which it is disengaged from said actuator into operative engagement therewith; a trigger pivotally mounted on said actuator and normally maintaining said interponent disengaged from said driven member; a re-setting cam face on said interponent;

a typing control mechanism including a settable element engageable with said trigger for moving said trigger in one direction about its pivot to release said interponent and enable it to move into engagement with said driven member whereby said actuator will be driven by said driven member to operate said typing member during the course of which operation said interponent is thrown out of engagement with said driven member; means for then returning said actuator towards its normal non-actuated position, said typing control mechanism including a manipulatable member operable for moving said settable element to its set position for engaging said trigger when said manipulatable member is operated, and for maintaining said settable member in its set position for repeatedly re-engaging said trigger when said manipulatable member is held in manipulated position thereby to prevent returning of said trigger to its normal position, whereby, during returning of said actuator towards its normal non-actuated position, said interponent will re-engage said driven member to be repeatedly driven thereby for effecting repeated driving of said actuator and repeated typing operations of said typing member; and means responsive to returning of said settable element to normal position for rocking said trigger reversely about its pivot to move a part of said trigger against said re-setting cam face and thus move said interponent from engagement with said driven member.

4. In power operating mechanism for a typewriting or like machine, a typing member; a power-driven member; an actuator; means connecting said actuator to said typing member; an interponent rockably mounted on said actuator for movement into operative engagement with said driven member and for reverse movement out of operative engagement with said driven member, and being biased to rock in one direction from a normal position in which it is disengaged from said actuator into operative engagement therewith; a trigger mounted on said actuator and normally maintaining said interponent disengaged from said driven member; means for rocking said interponent in the reverse direction for returning it from its operative position to its normal position; a typing control mechanism including a contactor, means mounting said contactor so as normally to be disengaged from said trigger but so as to be movable into engagement with said trigger for actuating said trigger to release said interponent and enable it to be rocked by its bias into engagement with said driven member whereby said actuator will be driven by said driven member to operate said typing member during the course of which operation said interponent is thrown out of engagement with said driven member, and a manipulatable member for moving said contactor into operative position for engagement with said trigger and holding said contactor in its operative position as long as said manipulatable member is held manipulated; and means for then returning said actuator towards its normal non-actuated position, said contactor, when in its operative position, being engageable with said trigger when said actuator returns towards its normal non-actuated position for holding said trigger in actuated, interponent-releasing position, whereby the bias on said interponent will maintain said interponent in position for re-engagement with said driven member, thereby effecting repeated driving of said actuator and

said typing member by said driven member while said manipulatable member is held in manipulated position.

5. In power operating mechanism for a typewriting or like machine, a typing member; a rotatable driven member; a movably mounted actuator; means operatively connecting said actuator to said typing member; an interponent mounted movably on said actuator; a spring urging said interponent to move into drive-transmitting engagement with said driven member; a trigger mounted movably on said actuator and normally occupying a position in which it maintains said interponent out of drive-transmitting engagement with said driven member; key-controlled means including a contactor normally disengaged from said trigger in any position of said trigger but being movable into an actuated position for engaging said trigger for moving said trigger to release said interponent and enable the latter to be moved by said spring into drive-transmitting engagement with said driven member, whereby said actuator will be driven through said interponent until the latter is thrown out of engagement with said driven member; means for urging said actuator to return to normal position upon such disengagement of said interponent from said driven member; an abutment engageable by said trigger when said actuator is so return-moved and said contactor is in its normal position for returning said trigger to its initial position on said actuator; and means associated with said trigger and said interponent for returning said interponent to its normal position when said trigger is returned to its initial position, said key-controlled means including mechanism for holding said contactor in its actuated position as long as the key of said key-controlled means is in operated position.

6. In power operating mechanism for a typewriting or like machine, a typing member; a rotatable driven member; a movably mounted actuator; means operatively connecting said actuator to said typing member; an interponent mounted movably on said actuator; a spring urging said interponent to move into drive-transmitting engagement with said driven member; a trigger mounted pivotally on said actuator and having a nose and a tail, and normally occupying a position in which said nose engages and maintains said interponent out of drive-transmitting engagement with said driven member; key-controlled means including a pivoted element having a contactor surface normally disengaged from said trigger tail in any position of said trigger, said element being rockable to an actuated position in which said contactor surface is engageable with said trigger tail for moving said trigger to release said interponent and enable the latter to be moved by said spring into drive-transmitting engagement with said driven member, whereby said actuator will be driven through said interponent until the latter is thrown out of engagement with said driven member; means for urging said actuator to return to normal position upon such disengagement of said interponent from said driven member; an abutment engageable by said trigger when said actuator is so return-moved and said pivoted element is in its normal position for returning said trigger to its initial position on said actuator; and means associated with said trigger and said interponent for returning said interponent to its normal position when said trigger is returned to its initial position, said

key-controlled means including mechanism for holding said pivoted element in its rocked position with said contactor surface positioned for engagement with said trigger tail as long as the key of said key-controlled means is in operated position.

7. In power operating mechanism for a typewriting or like machine, a typing member; a rotatable driven member; a movably mounted actuator; means operatively connecting said actuator to said typing member; an interponent mounted movably on said actuator; a spring urging said interponent to move into drive-transmitting engagement with said driven member; a trigger mounted movably on said actuator and normally occupying a position in which it maintains said interponent out of drive-transmitting engagement with said driven member; an abutment; means for effecting single stroke actuation of said typing member including key-controlled means for moving said actuator to move said interponent towards but not into engagement with said driven member and simultaneously to move said trigger into engagement with said abutment to thereby actuate said trigger to release said interponent and enable the latter to be moved by said spring into drive-transmitting engagement with said driven member, whereby said actuator will be driven through said interponent until the latter is thrown out of engagement with said driven member; means for urging said actuator to return to normal position upon such disengagement of said interponent from said driven member, a second abutment engageable by said trigger when said actuator is so return-moved for returning said trigger to its initial position on said actuator, and means associated with said trigger and said interponent for returning said interponent to its normal position when said trigger is returned to its initial position; and means including a repeat key for automatically effecting repeated actuation of said typing member as long as said repeat key is held depressed including an element formed with a contactor face normally positioned to be disengaged from said trigger in any position of said trigger, and connections between said repeat key and said element for moving said element in response to depression of said repeat key to a position in which said contactor face is engageable with said trigger when said actuator is in or is approaching its normal position for preventing said trigger from returning said interponent to its normal position.

8. Mechanism as set forth in claim 7 in which the connections between said repeat key and said element include a link operable by said repeat key; a shaft to which said element is attached; and an arm secured to said shaft and being pivotally connected to said link.

9. Mechanism as set forth in claim 8 in which said arm is curved and is thereby readily deformable for varying the relative locations of said shaft and said pivotal connection between said arm and said link.

WILLIAM H. KUPPER.
